UNITED STATES PATENT OFFICE.

ELBERT R. TILLINGHAST, OF UPPER MONTCLAIR, NEW JERSEY.

PROCESS OF SEPARATING THE STRANDS OF WOVEN FABRIC.

1,100,458.

Specification of Letters Patent. Patented June 16, 1914.

Application filed January 9, 1912. Serial No. 670,152.

To all whom it may concern:

Be it known that I, ELBERT R. TILLINGHAST, a citizen of the United States, residing at Upper Montclair, in the county of Essex and State of New Jersey, have invented certain new and useful Improvements in Processes of Separating the Strands of Woven Fabric, of which the following is a full, clear, and exact description.

10 This invention relates to a process of shredding or disintegrating fabric, such for example as carpet, for forming waste suitable for use in car journal boxes and analogous devices.

15 Attempts have been made heretofore to ravel carpet strips along the edges of such strips, for the purpose of making rugs in a well known manner. Attempts have also been made to fray narrow strips or ribbons 20 of fabric by pulling strands thereof apart.

As the raveling or fraying has usually been conducted heretofore the resulting strands from the weft, and frequently also those from the warp, have been cut or broken into 25 irregular lengths and many of these lengths have been objectionably short for many purposes for which they have been intended.

It is the object of the present process therefore to so handle the fabric that the 30 warp and weft threads thereof may be cut or otherwise divided into relatively determined lengths, when desired, while the weft is pulled away therefrom with a minimum amount of breakage, practically all of the 35 strands obtained being of considerable length.

If it be desired to unravel a section of carpet, the fingers or some pointed instrument or device could be used; and one or more 40 strands of the weft, for example, might be grasped by the hand and pulled away from the body of the section. The first strand or few strands of weft would separate quite easily. When, however, the warp has been 45 exposed even a comparatively short distance, owing to the interwoven connection between the warp and weft, the weft strands would be separated with increasing difficulty. If an attempt were made to forcibly pull these 50 interior weft threads or strands from, let us say, one end thereof, which would be the most convenient starting point, they would be apt to break.

If it be attempted to pick a group of weft 55 strands simultaneously along the length

thereof, considerable power would be required, and work expended. Further, the weft threads would be subjected to a relatively high tension, especially after a fair portion of the warp had been exposed by 60 previous raveling, the warp will tangle badly, and breakage is almost certain to result.

I have found that if a weft strand, and preferably but a single one of such strands, 65 be picked or pulled, starting, for example, at one side of a relatively wide strip of fabric, such as carpet, and if thereafter the same weft thread or strand be engaged or picked at a point along its length quite 70 closely adjacent the first, while thereafter a still further inwardly (or outwardly, as the case may be) positioned point is similarly directly engaged, and such successive engagements be continued in substantially like 75 manner at preferably regularly spaced intervals along the length of the weft, such threads may be stripped from the warp, especially if the picking operation be rapidly conducted, with practically a minimum 80 breakage of the weft or warp. In other words, I have found that the best way to ravel the weft is to positively engage a thread successively along spaced points 85 thereof while continuing to exert a pushing or pulling effort upon such points after they have been so engaged until such weft thread, or a considerable portion thereof, has been freed from the warp. The fabric should hence preferably be picked along lines more 90 or less obliquely disposed with respect to the general line of the warp as originally disposed in the fabric. I have also found that it is frequently desirable to provide 95 cuts in the fabric which extend in the direction of the weft so that but few weft threads are severed by such cuts, and to sever the weft into determined lengths, preferably independently of said cuts. The preferred disposition of these cuts may best be 100 discussed in connection with the drawings. I have exemplified herein mechanical means for effectuating my process. It will be understood, however, that I in no way regard the particular mechanism shown as essential to 105 my process, or indeed that any mechanism is absolutely necessary. For this reason only such parts of the said mechanism as are adapted to carry out certain steps of the process have been detailed.

Referring to the drawings in which like reference characters designate like parts throughout the several views: Figure 1 is a somewhat diagrammatic section of the said mechanism. Fig. 2 is a detail of a preferred form of picking drum used in said mechanism, the drum being shown in perspective. Fig. 3 is a similar view of a feeding drum or roll. Fig. 4 is a similar view of a pressure drum. Fig. 5 is a fragmentary detail of a finger bar with guiding or smoothing fingers thereon. Fig. 6 shows a section of carpet, or the like, with cuts or slits formed therein preparatory to shredding. Fig. 7 is a fragment of fabric with picks in position therein. Fig. 8 is a fragmentary detail of the air jet devices.

Considering again the subject of slitting the fabric in the direction of the weft, the carpet 1 shown in Fig. 6 is slit or cut in this fashion, as at 2, and it should be noted that each of these slits is relatively short in length, extending over merely a limited number of warp threads or strands. In practice these cuts may each be made about two inches long. They are further staggered with respect to each other so that each is advanced beyond the next adjoining slit about three-eighths or one-half inch, in the direction of the warp. It is preferable also to slightly overlap these cuts, as shown, so as to insure all of the warp being cut.

Since the fabric is nowhere completely severed across its width, at least not by these slits, it is evident that it may be most conveniently handled during the picking or shredding operation, and it may be here stated that this staggered cutting or slitting of the warp materially facilitates the stripping of the weft by, in the first place, preventing the exposed warp threads from growing to greater than a predetermined length and by not permitting them to break in an irregular manner here and there across the fabric. As a result the operation in question is rendered smooth and even, while the product is materially improved in several obvious respects; the warp strands being of substantially uniform length and the weft threads or strands being also in better condition. As a matter of fact, slitting the fabric in this manner so loosens the whole structure that it is most readily disintegrated.

Considering now the mode of effectuating the process in the mechanism illustrated, a brief detail description of this mechanism will be in order.

A suitable support 3 carries a pressure roll 4 mounted on a suitably journaled shaft 5. This roll is preferably circumferentially grooved as at 6, at intervals along the length thereof for the reception of spring fingers 7. These fingers are secured to a cross-bar 8 attached to the support 3,

and extend through the said grooves and between the roll 4 and a feed-roll 9. This latter has the surface thereof roughened in any suitable manner as by inserting thereinto numerous pins 10, which latter, it will be observed, are preferably somewhat rearwardly directed with respect to the direction of rotation of the roll 9; said roll rotating in the direction of the arrow thereupon in Fig. 1. The drum or roll 9 is preferably yieldingly mounted upon the shaft 11. To this end the respective ends of said shaft are each secured in the extremity of the short arm 12 of a bell crank. These cranks are loosely mounted upon a shaft 13, and the longer arms 14 of said cranks may be weighted, as at 15. Shaft 11 carries a sprocket wheel 16 which drives a sprocket 17, mounted on a counter-shaft 18, these sprockets being connected by a chain 19. Shaft 18 in turn drives the roll or drum 4 through the instrumentality of a crossed belt 20 and pulleys 21 and 22, the latter respectively disposed on the rear extremities of shafts 18 and 5.

The fabric to be treated is delivered to the roughened feed drum 9 by means of an apron or conveyer 23 of any suitable description. Shaft 11 also carries a spur gear 24 which is in mesh with a pinion 25 secured to the shaft 13 above referred to, and by means of the construction shown the feed drum may be forced away from the pressure drum, as by reason of the passage of a hemmed edge of carpet, or the like, without interfering with the drive either of the pressure drum or of the shaft 13. The latter carries a spur gear 26 which is in engagement with a pinion 27 mounted on a shaft 28, and the gears and pinion 24, 25, 26 and 27 are so proportioned that while the drum 9 may be rotated relatively slowly, a picker-drum 29 disposed on shaft 28 is driven at considerable velocity.

The picker-drum has been shown in detail in Fig. 2, and extends across the width of the fabric to be pulled apart. A series of picks 30, preferably somewhat bent, as shown, are arranged, preferably helically, around and outwardly projecting from, the drum surface; said drum being driven in the direction of the arrow thereupon. The points of the picks preferably barely clear the points of the pins 10 in the drum 9, and a pressure piece or plate 31 depends from the support 3 so that the edge 32 of said piece extends down almost into contact with both the picks and said pins. The edge 32 is preferably very slightly rounded, as, for example to a $1/32''$ radius.

The process as effectuated in this mechanism is substantially as follows: Assuming that carpet is the material to be treated, a strip 1 of the same is fed between the pressure and feed rolls from the conveyer 23.

The pressure roll 4 bears relatively lightly against the upper surface of the carpet but with sufficient force to drive it down upon the pins 10 which engage the fabric and thereby positively advance the same. The 5 spring fingers 7, it will be noted, extend almost to the pressure piece 31, and as their lower extremities are curved to substantially fit the feed roll, said fingers hold the carpet 10 well down on the pins 10 after it leaves the pressure roll. The advancing edge of the carpet passes under the inclined and wedging face 33 of the pressure piece and is thereby driven forcibly against the surface of the 15 feed drum. If a portion of the fabric happens to be of greater thickness than usual, the wedging action will force the feed drum rearwardly and downwardly away from the pressure piece, so that no breakage of the 20 mechanism can occur. In such event the fingers 7 continue to hold the carpet quite firmly against the feed drum so that the advance of the material through the machine continues uninterrupted. The fingers 7 25 further serve to smooth out the material while it is entering the rolls. Let us assume now that the forward edge of the carpet has just cleared the edge 32 of the pressure piece. Immediately thereafter a pick 30 upon the 30 rapidly rotating picker-drum is driven into the fabric and sharply pulls the strand of the weft with which it is in engagement forcibly upward and substantially at right angles to the line of travel of the fabric at 35 such point. This action tends to strip the strands away from the warp and hurl them by centrifugal force away from the picker drum. Excessive speed of this drum would of course cause the threads to be broken, 40 or chopped into short lengths, so that the speed thereof while rapid must be proportioned to the strength of the strands of the weft. Ordinarily the speed of the picker-drum is so proportioned to the speed of the 45 feed drum that one pick 30 will directly engage strand A, as shown in Fig. 7, while the next will engage said strand immediately thereafter and at a point quite closely adjacent to the point first engaged. Now while 50 the first strand may be quite readily pulled away from the warp, it is evident that the longer the exposed strands C of the warp, the more difficult will it become to strip the weft therefrom. There is hence also an increasing 55 tendency to disrupt the weft strands. This tendency is greatly increased if the pick engages strand B, back of strand A, and forces the latter from the warp by pressing strand B thereagainst. The weft strand A at the point when the pick 30' engages said strand, presses the adjacent warp threads, one in one direction and the other 60 in the opposite direction, whereas strand B at a point immediately back of the point 65 picked by 30' presses the warp threads in

reverse direction. It is obvious therefore that the bights so formed in the warp resist the disengagement of the plurality of weft threads therefrom by a single pick pushing or pulling against one thread directly and 70 against the one in advance indirectly. In other words, in order to efficiently ravel the fabric preferably but a single strand at a time should be picked therefrom, or at any rate one part of the strand should be spaced 75 from the corresponding portion of the next rearwardly disposed weft strand before the latter portion is materially disturbed. The picks have accordingly been disposed helically around the drum, so that as shown in 80 Fig. 7, one pick 30 will engage a weft strand, then the next pick 30' engages the same strand at a point which it will be observed has already been somewhat displaced by the action of the first pick, and so on. The 85 weft threads therefore are removed from the warp by having successive portions thereof bent around into a line which diverges from the normal line of the weft and the weft is smoothly removed from the 90 warp without undue strains in either warp or weft.

The cuts 2 in the fabric aid the operation and as soon as a warp strand has grown to a determined length, it simply drops or is 95 pulled away from the fabric. In order to prevent the weft from being unraveled into too great, or into irregular lengths, the fabric is slit or severed, preferably in the direction of the warp. This may be done at any 100 time prior or up to the time that the weft is stripped. In the mechanism herein described by means of which my process may be carried out, this severance of the weft strands is accomplished by means of two 105 circular knives 34 which are mounted upon the drum 29 and are preferably made slightly larger in diameter than the diameter of the space within which the picks 30 turn. To afford clearance for these knives, the 110 pressure piece 31 may be slotted or recessed as at 35. The knives slit the fabric, which is delivered to the machine approximately warpwise, in the direction of the warp and hence sever but few warp strands. They are 115 preferably so disposed along the length of the drum 29 that, assuming the width of fabric to be substantially that of the length of the drum, they will cut the fabric into three strips, the outer of which will be approximately half the width of the inner strip. This disposition of the knives is desirable owing to the fact that a weft thread A is normally integral with that designated B, so that the portions of the weft threads 120 pulled from the sides of the strip are unfolded and then substantially equal in length to the portions lying between the knives 34.

The number of knives used will, of course, 130

depend upon the lengths of weft ravelings desired, so that the provision of two knives is to be regarded as merely by way of illustration. This severance of the weft threads 5 preferably, but not necessarily, occurs just before the picks engage them. In claiming, therefore, a severance of the weft threads before the removal of the same from the fabric, I do not desire to be regarded as limiting myself to a severance substantially at 10 the moment of picking, nor even to a severance immediately before the last mentioned operation.

Considering next another feature which I 15 regard as of great importance in the process, and referring more particularly to Figs. 1 and 8 of the drawings, it will be observed that the face of the pressure piece or plate 31 is perforated at a plurality of points 36, 20 and that these perforations are in communication with a series of ducts or conduits 37 which open into a pipe 38. This pipe receives compressed air or other suitable pressure fluid from a suitable source of supply 25 of the same, such as a tank 39, through the instrumentality of a pipe 40. While the picking operation is in progress, streams of compressed air or the like are directed outwardly upon the pickers and perform a plurality of functions. In the first place the 30 air jets help to force the fabric (or the strands thereof) as it emerges from beneath the pressure piece, on to the points of the pickers. This tends to reduce the formation 35 of rags or chunks of undisintegrated fabric, which occurs if the teeth do not engage in the manner above described. In the next place the air jets or blasts, which are preferably somewhat downwardly directed, 40 serve to aid in cleaning away the strands, which might otherwise tend to wrap around the drum, from the mechanism. Most important of all, however, these blasts serve to substantially clean the product from dirt 45 and from what is known to the trade as "fly." This latter consists of short fragments of fiber, the presence of which is highly objectionable in journal box packing and the like. The "fly" and dirt is blown 50 away from the loosening strands of the fabric and falls or is directed downwardly while the heavier and longer threads or strands are drawn upwardly, at first slipping down upon the picks which are in engagement with them until they are disposed 55 substantially in a plane with the dot and dash line 41, and thereafter being hurled by centrifugal force upwardly and forwardly away from the deposited "fly" and dirt. It is to be understood, however, that 60 while I contemplate freeing the strands from the drum and teeth by centrifugal force I do not desire to be limited to this particular means for freeing said strands.

Having described my invention, I claim: 65

1. The process of separating the strands of a woven fabric which comprises forming groups of warp strands therein by discontinuously slitting the fabric substantially in the direction of the weft, so that the ends 70 of the warp strands in one group extend beyond the ends of the warp strands of an adjacent group, and thereafter picking the weft strands away from the so severed warp strands. 75

2. The process of separating the strands of a woven fabric which comprises forming groups of warp strands therein by discontinuously slitting the fabric substantially in the direction of the weft along parallel short 80 lines which are staggered with respect to each other, and thereafter picking the weft strands away from the said groups of warp strands.

3. The process of separating the strands 85 of a woven fabric which comprises slitting the fabric substantially in the direction of the weft along a plurality of parallel lines which are discontinuous, to cut substantially all the warp strands of the fabric at some 90 portion of their length, and thereafter stripping the weft away from the so severed warp by picking the weft strands singly and successively away from the warp.

4. The process of separating the strands 95 of a woven fabric which comprises stripping the weft strands from the warp by picking and positively engaging successive spaced apart portions along the length of successive weft strands and driving each of the so engaged weft strands from its engagement with the warp by bending successive portions of each of said strands around into a line which diverges from the normal line of the weft. 100

5. The process of separating the strands of a woven fabric containing sets of warp and weft strands which comprises stripping one of said sets of strands from the other set by picking and positively engaging successive portions along the length of each successive strand to be stripped, and driving each of said last mentioned strands from its engagement with the strands of the other set by bending successive portions of 110 each of said strands to be stripped around into a line which diverges from the normal line of such strand when in place in the fabric, while working gradually inwardly toward what had been the center of the 115 fabric, in the direction of the warp. 120

6. The process of separating the strands of a woven fabric which comprises stripping the weft strands from the warp by picking and positively engaging successive portions, 125 one after another, along the length of each successive weft strand, driving the said portions of each weft strand respectively away

from the adjacent and corresponding portions of the weft strand immediately behind, before displacing said corresponding portions from their respective positions in the 5 fabric.

7. The process of separating the strands of a woven fabric which comprises dividing both the weft and warp strands of said fabric into substantially determined lengths 10 and stripping the weft from the warp by sequentially picking and positively engaging each weft strand at successive points therein, and driving each said strand from its engagement with the warp at a plurality 15 of points along the length thereof substantially simultaneously.

8. The process of forming waste for lubricating purposes and the like which comprises gripping a woven fabric and pulling 20 substantially all of the weft and warp strands thereof apart by stripping one set of said strands from the other by sequentially picking successive spaced portions of the outermost strand of the set to be stripped 25 and thereafter similarly picking substantially successive strands, disposed substantially in parallelism with that first picked, one after another while gradually working inwardly toward what had been the center 30 of the fabric.

9. The process of separating the strands of a woven fabric which comprises stripping one set of said strands from the other by sequentially picking successive spaced portions of the outermost strand of the set to be stripped and thereafter similarly picking substantially successive strands, disposed substantially in parallelism with that first picked, one after another while gradually working inwardly toward what had been the center of the fabric.

10. The process of separating the strands of a woven fabric by picks which comprises picking apart the weft and warp of said fabric by positively engaging a strand thereof with a plurality of said picks at spaced points along the length of said strand at successive intervals, effecting a movement of each of said picks in determined parallel 50 planes, and effecting a relative movement between said picks and said fabric approximately parallel to said planes.

11. The process of separating the strands of a woven fabric which comprises effecting 55 a relative movement between said fabric

and a determined line and removing strands from said fabric at said line by picking substantially at right angles to said line at successive points, along substantially the entire length of said line at successive intervals. 60

12. The process of separating the strands of a woven fabric which comprises advancing said fabric toward a determined line and there picking away from said fabric strands thereof at successive points along 65 the length of said line at successive intervals, substantially one at a time.

13. The process of separating the strands of a woven fabric which comprises advancing said fabric toward a determined line 70 and there picking away from said fabric weft strands thereof at successive points along the length of said line at successive intervals, beginning at an edge of said fabric and working gradually into engagement 75 with previously unpicked weft strands.

14. The process of separating the strands of a woven fabric which comprises advancing one set of strands thereof substantially endwise toward a determined line and there 80 picking the strands of said fabric which are disposed substantially at right angles to said first mentioned set, bodily away from said fabric at successive points along the length of said line at successive intervals. 85

15. A process of separating the weft strands from the warp strands of a fabric which consists in picking the outermost weft strand, pulling said strand from the warp, picking said strand at a point adjacent said 90 first point while continuing the pulling at the first point and repeating the operation for successive portions of said strand and successive strands of the fabric.

16. The process of separating the weft 95 strands from the warp strands of a fabric which consists in picking and positively engaging successive spaced-apart portions along the length of successive weft strands at successive intervals, thereby pulling the 100 so engaged weft strand from its engagement with the warp strand by pulling successive portions of each of the strands into a line parallel to the plane of the picking.

In witness whereof, I subscribe my signature, in the presence of two witnesses.
